(57) **CLAIM**

The ornamental design for a beverage bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of beverage bottle according to an embodiment of my new design,

FIG. 2 is a side view thereof,

FIG. 3 is a perspective view thereof,

FIG. 4 is a top view thereof; and,

FIG. 5 is a bottom view thereof.

The shade lines shown throughout the figures are understood to represent contour of the claimed design only.
